WEDGE MAKING JIG

Reuben Johnson, Calgary, Alberta, Canada

Application December 22, 1952, Serial No. 327,299

3 Claims. (Cl. 143—52)

1 My invention relates to new and useful improvements in devices for making or facilitating the manufacture of wooden wedges, an object of my invention being to provide a device of the character herewithin described which enables wooden wedges to be made quickly and accurately and at the same time includes means whereby the finished size of the wedge may be controlled.

Another object of my invention is to provide a device of the character herewithin described which, in conjunction with the foregoing objects, permits a plurality of wedges to be made all having exactly the same dimensions.

Another object of my invention is to provide a device of the character herewithin described which can be used either with a hand saw or with a band or circular saw.

Still another object of my invention is to provide a device of the character herewithin described which is simple in construction, economical in manufacture, and otherwise well suited for the purpose for which it is designed.

With the foregoing objects in view, and such other objects and advantages as will become apparent to those skilled in the art to which this invention relates as this specification proceeds, my invention consists essentially in the arrangement and construction of parts all as hereinafter more particularly described, reference being had to the accompanying drawings in which:

Figure 1 is a perspective view of my device. Figure 2 is a top plan view of my device showing a finished wedge in situ.

Figure 3 is a side elevation of my device.

Figure 4 is a view substantially along the lines 4—4 of Figure 2.

Figure 5 is a fragmentary top plan view of one side of the base plate showing the wedge-shaped recess therein.

In the drawings like characters of reference indicate corresponding parts in the different figures.

Unless special equipment is available, the cutting of wedges presents considerable difficulty and as the efficiency of a wedge depends directly upon the dimensions thereof, it is desired that wedges be cut as accurately as possible.

Furthermore, when a series of wedges is being used, it is essential that they be similar in all respects in order that wedging effect may be equal. The disadvantages and difficulties of cutting wedges by hand without the advantage of a jig is overcome by the device hereinafter to be described, inasmuch as it not only provides a jig for holding the lumber while the wedge is

being cut, but controls both the length and width of the finished wedge.

Proceeding now to describe my invention in detail, it will be seen upon reference to the accompanying drawings that I have illustrated a substantially rectangular base plate 1 having a handle 2 secured upon the upper surface 3 thereof and slightly to one side of the base plate.

The side 4 of the base plate is provided with a wedge-shaped recess 5, said recess connecting at a point 6 and increasing in depth to a maximum at the wall 7 and it will be observed that this recess extends clear through the thickness of the base plate 1.

What I define as a wedge-width gauging plate 8 is mounted within this recess, said gauging plate consisting of a vertical centre portion 9 extending substantially the full length of the recess 5 and having a horizontal flange portion 10 extending at right angles from one side of the centre portion 9 and adapted to overlie the upper surface 3 of the base plate 1. It will be seen that in this embodiment, the vertical centre portion and the horizontal flange portion are formed from one piece of stock which is angulated to give the desired component. The gauging plate 8 is pivotally secured to the upper side 3 of the base plate 1 by means of a pivot pin 11 passing through one end of the horizontal flange 10 and being anchored to the base plate 1 so that the gauging plate 8 can be swung in an arc around pivot 11. Means to secure the gauging plate 8 in the desired position are provided and take the form of a slot 12 formed in the horizontal flange through which extends a bolt 13 which also passes through an aperture 14 within the base plate. A wing nut 15 engages the bolt and supplies clamping pressure to hold the gauge plate in the desired position.

A perusal of the drawings and consideration of the foregoing will show that the vertical centre portion 9 of the gauge plates limits the effective width and slope of the wedge 16 being formed.

Means are also provided to control the length of the wedge, said means taking the form of a U-shaped clip 17 which hooks over the upper edge 18 of the gauging plate so that the longer legs 19 of the clip extend downwardly over the outer surface 20 of the vertical centre portion 9. This clip may be slid along the vertical centre portion and is anchored in position by means of a clamp bolt 21. From this it will be seen that the effective length of the wedge may be controlled as shown in Figure 2.

In operation, the finished width of the wedge 55 and the effective length are decided by position-

ing the gauging plate 8 as heretofore described and also by positioning the clip 17 whereupon a piece of the lumber is placed within the wedge-shaped recess 5 and the surplus material cut off parallel to the edge 4 of the base plate, thus leaving the wedge 16 as shown in Figure 2.

However, if it is not desired to use a hand saw in this operation, I have provided means whereby the device may be used upon a band or circular saw table. In this connection, I have provided a rail 22 upon the underside of the base plate 1, it being appreciated that said rail is adapted to engage one of the guide grooves on a conventional saw table. It will be appreciated that this rail has to be adjustable so that the saw can make a cut adjacent the edge 4 of the base plate. I have, therefore, mounted the rail within a pair of transverse rail carriers 23 mounted upon the upper side of the base plate 1 and at each end thereof. These carriers are provided with transverse blocks 24 and are engageable by bolt or pin 25 extending upwardly from each end of the rail 22, wing nuts 26 clamp them in position as desired.

Alternatively, the device may be moved via the handle 2 along the conventional circular saw fence which in itself may be adjusted transversely with relation to the saw blade.

From the foregoing, it will be appreciated that I have provided a universal jig from which may be manufactured a plurality of wedges having similar dimensions and which furthermore may be adjusted simply and easily if the dimensions of the wedge have to be altered.

Since various modifications can be made in my invention as hereinabove described, and many apparently widely different embodiments of same made within the spirit and scope of the claims without departing from such spirit and scope, it is intended that all matter contained in the accompanying specification shall be interpreted as illustrative only and not in a limiting sense.

What I claim as my invention is:

1. A jig for facilitating the manufacture of wooden wedges, comprising in combination a horizontal base plate, a recess formed in one side of said base plate, and a wedge-width gauging plate pivotally secured to said base plate and swingable within said recess, and means for selectively locking said gauge plate in the desired position within said recess, a longitudinally extending rail upon the underside of said base plate, transverse rail carriers secured to the ends of said base plate, said rail carriers being slotted transversely relative to the base plate, and means coacting between said rail and said carriers whereby said rail may be moved laterally across the base of said base plate and secured in the desired position.

2. A jig for facilitating the manufacture of wooden wedges, comprising in combination a horizontal base plate, a recess formed in one side of

said base plate, and a wedge-width gauging plate pivotally secured to said base plate and swingable within said recess, and means for selectively locking said gauge plate in the desired position within said recess, said wedge-width gauging plate comprising a vertical centre portion extending substantially the full length of said recess, a horizontal flange extending at right angles from said centre portion and overlying said base plate, said gauge plate being pivotally secured to said base plate via one end of said flange, and means coacting between said base plate and said flange to position said gauge plate in the desired location within said recess, a longitudinally extending rail upon the underside of said base plate, transverse rail carriers secured to the ends of said base plate, said rail carriers being slotted transversely relative to the base plate, and means coacting between said rail and said carriers whereby said rail may be moved laterally across the base of said base plate and secured in the desired position.

3. A jig for facilitating the manufacture of wooden wedges, comprising in combination a horizontal base plate, a recess formed in one side of said base plate, a wedge-width gauging plate pivotally secured to said base plate and swingable within said recess, means for selectively locking said gauge plate in the desired position within said recess, and further means for adjusting the length of the wedge being formed, said base plate including a vertical centre portion extending substantially the full length of said recess, a horizontal flange extending at right angles from said centre portion and overlying said base plate, said gauge plate being pivotally secured to said base plate via one end of said flange, means coacting between said base plate and said flange to position said gauge plate in the desired location within said recess, and a longitudinally extending rail upon the underside of said base plate, transverse rail carriers secured to the ends of said base plate, said rail carriers being slotted transversely relative to the base plate, and means coacting between said rail and said carriers whereby said rail may be moved laterally across the base of said base plate and secured in the desired position.
